TENSION BAR AND LOCK

Filed May 10, 1929.

UNITED STATES PATENT OFFICE

PAUL K. MARSHALL, OF PITTSBURGH, PENNSYLVANIA, ASSIGNOR TO THE HIGGIN MANUFACTURING COMPANY, OF NEWPORT, KENTUCKY, A CORPORATION OF WEST VIRGINIA.

TENSION BAR AND LOCK

Application filed May 10, 1929. Serial No. 361,935.

My invention relates to means of fastening closures, such as shades and curtains for windows, and has particular application to window screens of the type in which a flexible wire screen element is held under tension upon a spring roller in a housing at the top of the window, so that, by means of a tension bar, it may be drawn down and fastened to cover the opening, or retracted into the housing at will. In such screens a spring latch is desirable for fastening the tension bar to the window sill when the screen is in use. When it is desired to open the screen, and the latch is released the screen moves toward the housing, carrying the tension bar with it, unless the operator manually holds them down. Thus, if the housewife desires to open the screen temporarily, for example, to place articles in an outside refrigerator, she must use one hand to hold the screen in place. If she does not, the tension bar is drawn up out of reach, and she is put to considerable inconvenience in closing the screen again. Further, if the spring roller is too tight, the impact of the tension bar against the housing would tend to loosen and rip away the screen element from its fastenings, and materially shortens the life of the device.

It is an object of my invention to provide the tension bar with a positive friction lock which will hold it at any position along the guides which is desired by the operator, and which will prevent the sudden flying up of the bar, and this enables me to use heavy spring tension on the roller, so as to keep the screening taut and smooth at all times.

It is a further object of my invention to provide a tension bar and lock which is simple and economical to construct, and which affords convenient means for the attachment of the screen element thereto.

These and other objects of my invention will be apparent to one skilled in the art upon reading these specifications.

In the drawings:

Figure 1 is a perspective view of the screen assembly, with portions of the frame cut away.

Figure 2 is a section of the tension bar and lock along the line 2—2 in Figure 1.

Figure 3 is a transverse section through the bar, showing one of the locking bars in section, one of the handgrips in elevation, and the method of attachment of the screen to the tension bar.

The entire assembly may be mounted in a window frame. I show a sill 3, side strips 4—4, which are secured to the window frame, and a screen or curtain box 5. This box joins a housing for the spring roller 6, and contains mountings of the ordinary type for the spring roller pins 7. Upon the roller is mounted a flexible screen element 8, usually specially woven of the correct width. It will be seen that the action of the roller is to hold the screen under tension and to retract it into the housing 5 unless it be drawn down by the tension bar, which is designated as 1 in Figure 1.

Each of the strips 4 is provided with a channel 9, the opening of which is partially closed by a projection so that sufficient room only is allowed for the easy entrance and movement of the screen element and the locking bars, as will hereinafter be more fully described. This projection is conveniently provided by strips 10 fastened removably to the strips 4, and of such width as to extend partially across the opening of the channel 9, forming a shoulder and a slotted opening. This will be clearly understood by reference to the section in Figure 2. The width of the screen element 8 will be such as to effect an insect-proof construction along the side strips, and may be sufficient to permit the screen to enter the slot between the rear wall of each strip 4 and its strip 10.

In the manufacture of metallic-frame window screens, it is the usual practice to form channel-shaped members of sheet metal, which provide the necessary stiffness and strength, and to fasten the screen into the channels thereof. In my tension bar, I provide a relatively deep and narrow sheet metal channel with its edges bent in toward each other, which is shown in section at 11 in Figure 3. The lengthwise slot thus left between the inwardly bent edges is disposed

upwardly, and the lower end of the screen element is fastened thereinto by any suitable method such as riveting, crimping, etc. In my improved construction, however, I prefer to double the end of the screen about a narrow metallic spline 12, and to slide this into a sheet metal member of U-shaped cross section, wedging upward therein. Advantages of this construction are that it provides a positive fastening for the screen element, facilitates the assembly of the tension bar and lock, and permits the ready disengagement of the screen element therefrom when desired.

15 Within the lower part of the tension bar channel 11, I provide locking bars 14 and 15, shown in Figure 2. These locking bars project beyond the tension bar channel at either end, and carry upon their extremities friction lugs 16, 16. The bars are free to slide in the channel, and are normally drawn toward each other by the action of the spring 17. Since each friction lug is disposed within the hollow portion of a respective frame strip 4, and bears against the shoulder formed by the strip 10, it will be clear that the action of the spring 17, in drawing them together by means of the locking bars, will be to lock the tension bar assembly securely and prevent its movement along the strips 4.

20 To release the lock I provide extensions of the locking bars which are designated at 18 and 19 in Figure 2, forming shoulders for the attachment of the spring 17, and overlapping portions for the attachment of the finger-grips 20 and 21. This construction is contained within a protuberance in the tension bar channel member, which I have designated at 22. This protuberance is slotted 25 for the passage of the finger-grip shanks, as at 23. The finger-grip shanks are fastened to the ends of the extensions 18 and 19 by any convenient method, such as by riveting, or by screwing the threaded shank into a threaded opening. It will be understood, of course, that instead of using separate finger-grips, these may be struck up from the extensions 18 and 19 and be integral therewith. The finger-grip 21 is thus fastened directly 30 to the end of the extension 19; but the shank of the finger-grip 20 first passes through a slotted opening 24 in the extension 18 before being fastened to the extension 19. The pressure of the fingers of the operator against 35 the finger-grips will have the effect of opposing the spring 17, and of forcing the locking bars in opposite directions outwardly from the ends of the tension bar channel, thus releasing the pressure of the friction lugs 16 against the shoulder formed by the strip 10. This permits the operator to raise or lower the screen as desired; and as soon as the finger-grips are released, the tension bar is immediately locked against movement, 40 and the screen is held at the desired height.

It will be noted that the tension bar structure can be removed and new wire inserted therein by merely unscrewing the strips 10 from the side bars.

Having thus described my invention, what I claim as new and desire to secure by Letters Patent, is:—

1. A tension bar and lock for a flexible closure, comprising a sheet metal channel member formed of a single stamping and provided with an enlargement in one side forming a housing, opposed locking bars slidably held within said member, one end of each of said locking bars projecting from an opposite end of said member and provided with a friction element, the other ends of said locking bars having means forming shoulders and overlapping portions within said housing, a finger grip-element on the overlying one of said portions extending through a slot in said housing, a second finger-grip element on the underlying one of said portions extending through a slot in the overlying one of said portions and through a slot in said housing, and a coiled spring within said housing attached to said shoulders.

2. A tension bar and lock comprising a hollow member with a slot in one side, bars parallel for portions of their lengths lying inward from said slot, and each having a projection out through a respective opposite end of said hollow member, engaging means on the respective projections, a single spring connecting the two bars and normally pulling said bars inwardly of said hollow member, and handles on the respective bars extending laterally outward through said slot.

3. A tension bar and lock comprising a channel with converging edge portions leaving a slot for entrance of a closure element to wedge between said edge portions, and leaving a space below the closure, said channel having a slot opening from one side of said space, locking bars slidably mounted in said space and yieldingly held with their end parts out past the respective ends of the bar, and handles on the respective bars extending out through said side slot.
